FLATWARE SURFACE FINISHING MACHINE

James W. Weatherell, Arthur Baron, and Francis R. Chesner, Olean, N.Y., assignors to Clair Mfg. Co. Inc., Olean, N.Y.

Filed Apr. 15, 1971, Ser. No. 134,551

Term of patent 14 years

Int. Cl. D15—09

U.S. Cl. D37—1 A

FIG.1

FIG.3

FIG2

FIG4

FIG. 1 is a front end elevational view of a flatware surface finishing machine;

FIG. 2 is a rear end elevational view thereof;

FIG. 3 is a top plan view thereof; and

FIG. 4 is a side elevational view thereof showing one form of end casing.

We claim:

An ornamental design for a flatware surface finishing machine, as shown and described.
